STORAGE TANK

Filed Aug. 30, 1928

UNITED STATES PATENT OFFICE.

ROBERT R. WADDINGTON, OF ROSELLE, NEW JERSEY.

STORAGE TANK.

Application filed August 30, 1928. Serial No. 302,968.

This invention relates to an improvement in storage tanks or the like and more particularly to an improved sealing arrangement to permit a large tank to be substantially gas or vapor tight, while allowing the necessary relative movement between the tank walls due to the expansion or contraction which commonly occurs as a result of the temperature changes to which a tank of 10 this character is exposed.

The present invention is particularly directed to an arrangement providing an expandable and contractible joint between the roof or top wall of a large storage tank and 15 the side or vertical wall thereof. Due to the size of these tanks and to the wide range of temperatures to which they are ordinarily exposed, there is considerable variation in the dimensions thereof in accordance with 20 surrounding temperature conditions. It has therefore proved difficult to make tanks of this character which will remain substantially vapor tight. The loss of the volatile constituents of the stored material, such for example as gasoline, may be quite high unless the storage tank is provided with sealing means to prevent the same. The present invention is particularly designed to afford 25 sealing means of this character which may be associated with commonly used roofing materials and which may be arranged in the general plane of said materials so as to be in a protected position and to avoid ribs, 30 projections or the like which may be easily damaged. More specifically the invention is directed to an arrangement which permits the use of flexible folded material in order to provide a substantially gas or vapor-proof seal. In accordance with this invention, one 35 or more sheets of the folded flexible material may be turned back upon itself in order to provide superimposed laminae which may lie substantially in the plane of the roof covering and be protected by the outside layer of 40 the same. When relative movement occurs between adjoining edges of the vertical and horizontal walls of the tank, the parallel superimposed portions move in relation to 45 each other, such a movement being permitted 50 by the flexible fold or folds therebetween.

In the accompanying drawings:

Fig. 1 is a sectional view through a joint between the vertical and horizontal walls of a storage tank provided with a seal con-

structed in accordance with this invention; 55

Fig. 2 is an enlarged view of the folded portions of the sealing sheets, these portions being more or less conventionally represented in order to afford clarity of illustration;

Fig. 3 is an enlarged sectional view of the 60 portion of the joint which is associated with the eave flange.

Referring to the accompanying drawings and more particularly to Fig. 1 thereof, the numeral 1 designates the vertical wall of a 65 storage tank which is provided with the usual outstanding angular member 2 providing an eave flange 8. The top wall 4 of the tank may comprise the conventional rafters which carry the ordinary wooden 70 sheathing or deck boards 5. Any suitable layers of roofing material may be applied to the boarding 5. For example, the body portion of the roof may be covered with one or 75 more layers of sized paper which are designated in general by the numeral 9. This paper may be covered with any suitable coating such as a silicate of soda solution. Preferably the paper layers, as designated by numeral 9, extend to the edge of the roof- 80 ing 5.

Located above the edge of these layers are the flexible sealing sheets to which the present invention more particularly pertains. For example, the sheet 10, which may be formed of 85 any suitable flexible material such for example as a suitably treated or impregnated canvas, a sheet of thin flexible metal, or any other suitable material of the desired characteristics, has its inner edge adhesively secured to 90 the upper face of the paper layer 9, this portion of the sheet 10 being designated by numeral 11. Suitable fastening means such as 95 nails 120 may also be applied to this portion of the inner sealing sheet. Outwardly of the edge portion 11 of the sheet, it is folded back upon itself as designated by the numeral 12 to provide a plurality of superimposed 100 laminae. Thus, for example, as illustrated in Fig. 2, there may be three layers of the flexible material, the intermediate layer being connected to the upper and lower layers by the folds 13 and 14. The upper and lower laminae of the folded sheet portion which 105 adjoin the folds are free from attachment to juxtaposed surfaces so that the relative movement between the laminae may occur, the flexibility of the folds permitting the same.

The upper layer of the folded portion of sheet 10 is continued to provide a down-turned marginal portion 15, Fig. 1, that may be adhesively secured to the upper edge of the 5 vertical wall 1 and preferably to the inner face thereof. For this purpose, I preferably first coat the inner face of the upper portion of wall 1, as well as flange 8 and the space therebetween with elastic cement designated by numeral 17, applying to this cementitious layer a suitable fabric strip 18 which has one margin affixed to the horizontal flange and the other margin affixed to the adhesive coating upon wall plate 1. Preferably the sheets 10 and 18 are arranged between the edge of the boards 5 and the upper edge of the vertical wall to provide a triangular recess that is filled with elastic cement 20, this cementitious material extending downwardly over the 15 surface of sheet 18 to provide the adhesive coating to which the margin 15 of sealing element 10 is applied. If desired, a suitable paper layer 25 may be disposed upon the horizontal flange 8 before the fabric strip 18 is applied thereto.

Preferably a second sealing strip or sheet 30 is arranged above the sheet 10. Either or both of these sheets may be of substantially vapor-tight, flexible material. Sheet 30 preferably may have a marginal portion extending inwardly over the inner edge of the lower sheet and being adhesively affixed to the outer face of the paper layer 9 by a bituminous cement or the like. The sheet 30 preferably includes a folded intermediate portion 31 which is arranged outwardly of the similar folded portion of the sheet 10. The upper fold of sheet 30 is continued outwardly in a generally horizontal direction to substantially the 40 outer edge of the flange 8. Preferably a suitable paper layer 31 may be disposed between the horizontal portion of sheet 18 and the adjoining face of the sealing strip 30 being extended to separate the latter from the elastic cement 20. Located inwardly of the folded portions of strips 10 and 30 may be alternate layers of roof sheeting, such as felt and plastic roofing material, such as an asphalt or bituminous composition designated by numerals 35 and 36, respectively. Disposed above the outer portion of sheet 30, I may provide a layer of more or less plastic cementitious material, for example an asphalt-asbestos composition designated by numeral 37. Superimposed upon the entire roofing assembly 50 may be a layer of comparatively stiff roof sheeting 39, the edge portion thereof overlapping the flange 8 and being embedded in a layer 40 of plastic cementitious material arranged above flange 8.

It is evident that the vertical wall of the tank tends to move relatively to the adjoining edge of the top or horizontal wall 4 thereof and that the sealing means described above 65 is effective in providing a substantially vapor

tight joint while permitting such relative movement. When movement of this character occurs, the superimposed layers of the sealing sheets tend to move relative to each other. Thus, for example, when the metal 70 wall 1 moves away from the edge of the roof 4, the flexibility of the sealing sheets permits the intermediate layer or run of the folded portion thereof to become shortened. The edge of the comparatively stiff sheet material 75 39 which is arranged in the plastic cement 40 may move inwardly and outwardly in relation to the latter, which is arranged to provide a substantially moisture proof seal but which would not necessarily prevent leakage of vapor, the latter being prevented by the arrangement of the sealing sheets and the plastic cement. It is further evident that the arrangement of the folded sheets substantially in the plane of the roofing material and with the 80 edge portions thereof in protected positions, i. e. directly above the horizontal flange 8 and affixed to the inner surface of the vertical wall provides an expandable joint construction utilizing flexible sealing sheets which 85 may be arranged in protected locations.

I claim:

1. A storage tank comprising walls in intersecting planes, a flexible sealing sheet connecting marginal portions of the walls, said sheet 95 having edge portions secured to the walls and having an intermediate folded portion to permit ready relative movement between its edge portions.

2. A storage tank comprising walls in intersecting planes, a flexible sealing sheet connecting marginal portions of the walls, said sheet having edge portions secured to the walls and having a portion turned back upon itself to provide substantially parallel sheet 100 portions connected by a fold whereby relative movement between the sheet edges may readily occur.

3. A storage tank comprising walls in intersecting planes, a flange on one wall lying in the same general plane as the other wall, a flexible sealing strip between said walls, said strip having edge portions secured to the flange and to the adjoining part of the other wall, superimposed portions of the strip being arranged parallel to each other and connected by a fold, said parallel portions being movable relative to each other when the flange moves away from or toward the edge of the other wall due to heat expansion and contraction.

4. A storage tank comprising a vertical wall and a top wall, a flexible sealing strip therebetween, said strip having edges connected to juxtaposed portions of the walls, said strip having a turned back portion between substantially parallel portions, the planes of said portions extending in the same general direction as one of the walls.

5. A storage tank comprising a vertical wall and a top wall, a flexible sealing strip 130

therebetween, said strip having edges connected to juxtaposed portions of the walls, said strip including a portion turned back upon itself to provide a fold, the edge of the 5 strip being connected to the interior of the vertical wall.

6. A storage tank comprising walls in intersecting planes, a plurality of flexible sealing sheets connecting marginal portions of 10 the walls, said sheets each having edge portions secured to the walls and having an intermediate folded portion to permit ready relative movement between its edge portions, said folded intermediate portions of adjoining

sheets being substantially beside each other. 15

7. A storage tank comprising walls in intersecting planes, a flexible sealing sheet connecting marginal portions of the walls, said sheet having edge portions secured to the walls and having an intermediate portion 20 turned back upon itself to provide a multiplicity of substantially parallel sheet portions connected by folds whereby relative movement between the sheet edges may readily occur. 25

Signed by me at New York City this 28th day of August, 1928.

ROBERT R. WADDINGTON.
